US00D896865S

(12) **United States Design Patent** (10) **Patent No.:** **US D896,865 S**
(45) **Date of Patent:** ** *Sep. 22, 2020

(54) **SURVEILLANCE CAMERA ENCLOSURE**(71) Applicant: **Parabit Systems, Inc.**, Roosevelt, NY
(US)(72) Inventor: **Mohammad Hasani**, Brooklyn, NY
(US)(73) Assignee: **Parabit Systems, Inc.**, Roosevelt, NY
(US)

(*) Notice: This patent is subject to a terminal disclaimer.

(**) Term: **15 Years**(21) Appl. No.: **29/674,829**(22) Filed: **Dec. 26, 2018**(51) LOC (12) Cl. **16-01**

(52) U.S. Cl.

CLAIM

The ornamental design for a surveillance camera enclosure, as shown and described.

DESCRIPTION

FIG. 1 is a front, top, right perspective view of a surveillance camera enclosure showing my new design;
 FIG. 2 is a front elevational view thereof;
 FIG. 3 is a right side elevational view thereof;
 FIG. 4 is a left side elevational view thereof;
 FIG. 5 is a rear elevational view thereof;
 FIG. 6 is a top plan view thereof;
 FIG. 7 is a bottom plan view thereof; and,
 FIG. 8 is a rear, top, right perspective view thereof.

The broken lines shown in the Figures depict portions of the surveillance camera enclosure that form no part of the claimed design.
